[57] **CLAIM**

The ornamental design for a lug removal tool, as shown and described.

DESCRIPTION

FIG. 1 is a perspective view of a lug removal tool showing my new design in the environment in which it is intended to be used, it being understood that the broken lines are for illustrative purposes only and form no part of the claimed design and

FIG. 2 is an exploded view of FIG. 1.;
The surface or portion of the article not shown in the drawing or described in the specification form no part of the claimed design.

1 Claim, 2 Drawing Sheets

FIG. 2
